TAPING MACHINE

Charles Hess, Yonkers, N. Y., assignor to S & S
Corrugated Paper Machinery Co., Inc., Brook-
lyn, N. Y., a corporation of New York

Application September 25, 1941, Serial No. 412,214

10 Claims. (Cl. 164—68)

My invention relates to devices for automatically taping the seams of paper boxes, cartons, or the like, and is particularly directed to mechanism for cutting the tape to the proper length.

In machines of the class described, it is preferable to deliver the tape to the carton seam in strips of definite length and to allow sufficient time between the delivery of each successive strip to permit the successive cartons to be brought into position to receive the tape.

In accordance with my present invention, I provide a tape-feeding mechanism in conjunction with a novel tape-feeding device and cut-off apparatus.

Various types of cutting apparatus or tape feeding devices have heretofore been used. However, most of these devices have depended upon an intermittent non-rotary motion. That is, a shear or guillotine cutter was so arranged to be suddenly actuated at the moment the proper length of tape was fed and was held stationary at all other times.

An important object of the present invention is the provision of a rotary knife for tape-cutting mechanism.

Another important object of the present invention is the provision of intermittent driving means for the rotary knife in order that appropriate lengths of tape may be fed at the proper time.

Still another object of the present invention is the provision of tape-cutting mechanism which will feed and cut the appropriate length of tape and apply the same.

These and many other objects of my invention will become apparent in the following description of a preferred embodiment thereof, taken in connection with the drawings in which:

Figure 1 is a general schematic view of one embodiment of my invention shown in perspective.

Figure 2 is a cross-sectional view taken along line 2—2 of Figure 1.

Figures 3 and 4 are cross-sectional views taken respectively along lines 3—3 and 4—4 of Figure 2, looking in the direction of the respective arrows.

Figure 5 is a cross-sectional view taken along line 5—5 of Figure 1.

Figure 6 is a cross-sectional view taken along line 6—6 of Figure 2.

Referring now to Figure 1, a control shaft 10 is rotated by pulley 11 and belt 12 from pulley 13 on driving shaft 14. A notched disc 20 with a pawl 21, pivoted at 23 and held against the disc 20 by spring 22 is provided to prevent reverse

rotation of the shaft 10 should the shaft 10 be stopped at any time in such a manner as to develop any back-lash.

Control shaft 10 also carries cam 24 which operates in a manner hereinafter described.

Friction disc 25 is also mounted on control shaft 10 and rotates friction pinion 26 slidably mounted on shaft 31 by means of key 30.

Shaft 31 is fitted with bevel gear 50 which engages with bevel gear 52 of shaft 34. Through pulley 35 and belt 36, shaft 34 turns pulley 37 and shaft 38.

Rotation of shaft 38 causes the rotation of feed pulley 40 and idler pulley 41 at a rate predetermined by the distance of the friction pinion 26 from the center of the friction pulley 25; the greater the distance, the greater the speed.

Thus the strip of tape 43 is fed from the roll of tape 42 at a constant rate. This rate of speed may be adjusted to suit the length of strips to be used by means of the handle having threaded end 51 engaging with the bearing nut 52. Nut 52 alters the center distance between pulleys 25 and 26 along the keyed parts of the shaft 31.

After being unwound from roll 42 by the feed pulleys 40 and 41, tape 43 passes between pulleys 44 and 45 which permit it to form a loop 46. Tape 43 then passes around guide pulley 63 and moistener roller 64 which rotates in a liquid container 65 and finally to the feed pulleys 70 and 71.

Tape 43 is of a type well known in the art, preferably a paper strip having adhesive material on one side thereof.

Moistener 64—65 serves to wet the adhesive to permit the seam-joining action of the tape 43 in a manner well-known.

Pulleys 70 and 71 perform two functions, namely that of guiding the end of the tape to its proper position at the beginning of the seam to be taped, as well as that of feeding a predetermined length of tape to the seam prior to its being cut off by the cutting apparatus hereinafter described.

Pulley 70 is an idler pulley. Pulley 71 on shaft 72 is rotated by pinion 73 which engages with rack 74. Rack 74 is moved in the direction of the arrow once on each revolution of the shaft 10 by means of cam 24 which is brought to bear against the cam follower 76. Spring 75 acts in a direction to oppose the rack motion due to cam 24. Shaft 72 is thus activated to move in an intermittent reciprocatory manner.

Reverse rotation of the feed pulley 70 and 71 may be prevented by a ratchet incorporated with in the pulley 71, in a manner which is now well

known, so that the direction of rotation of the pulley 71 may be uni-directional. This may, as will be obvious, comprise a pawl on shaft 72 and a ratchet in the interior of pulley 71 (see Figure 5).

The length of tape, which is to be fed for any box-sealing operation, may be predetermined by an adjustment including the handle 100.

The handle or member 100 may be moved in any suitable manner in order to cause the link 102 to rotate about the pin 103. For this purpose the handle 100 and the link 102 are interconnected by a pin 101.

The end 105 of the link member 102 bears against the extension 104 of the rack 74. The position of the end 105 of the link 102 determines the extent to which the rack 74 will return under the influence of the spring 75.

When the handle member 100 is so adjusted that the rack 74 may return to its full extent, then the cam 24 will engage the cam follower 16 during its entire period of rotation and hence will serve to feed the longest possible length of tape which may be fed by the device.

Should the handle member 100 be so adjusted however as to permit the rack 74 to return only slightly under the influence of the spring 75, then the cam 24 will contact the follower 16 only during a small portion of the revolution of the shaft 10 and consequently will feed a very short length of tape.

By appropriate adjustment between extremes, any desired length of tape may be fed and cut, depending on the length of the box which is to be taped.

The cartons or boxes 80, 80 which are to be taped are fed in the direction indicated by the arrow by the upper side of belt 81, the boxes 80 being spaced apart from each other a sufficient distance to correspond to the desired length of tape and the other adjustments of the mechanism.

The boxes 80 may preferably be fed by a feed roller 85 mounted on shaft 86 which, at one end thereof, carries the gear 87 meshing with gear 88 which in turn is mounted on shaft 14, thus insuring that the feed of the boxes will be integrated with the speed of movement of the remainder of the mechanism.

Likewise, belt 81 may be driven by gear connections or any other suitable manner to ensure appropriate relationship between the speed of movement of the boxes and the taping operation.

Pressure rollers 95, 95 may be utilized after the taping operation has been effected in order to press down the tape 43 over the seam to which it has been applied.

The type of taping mechanism herein described corresponds quite closely to that set forth in Patent No. 2,248,744, issued to the assignee of the present application.

The improvement in the present machine resides in the manner of effecting the cut-off when a sufficient quantity of tape has been applied.

The tape 43, after it is fed between the rolls 44 and 45 is fed by the feed rolls 70 and 71 between the blades of the cutting mechanism 120. It may then be captured beneath the feed roll 85 which, in Figure 1, is shown cut-off in order that the remainder of the apparatus be seen, but which is seen in full in Figure 5.

As is seen in Fig. 5, the feed roll 85 has a complementary roll 85' which also cooperates in feeding the boxes 80.

The cutter, as may be seen more particularly in Figure 5, consists preferably of a stationary knife blade 121 secured by bolts 122 to a block 123 which is mounted in any suitable manner on the frame of the machine.

The knife blade 121 may be adjusted in any suitable manner by adjusting screws 124 rotatable in threaded perforations in the block 123 and the adjusting screws 124 may be locked in position 10 by lock nuts 125.

The other knife blade 128 is secured in any suitable manner, as, for instance, by the bolts 131, to the knife shaft 132.

Knife shaft 132 is driven by the rack 140 and pinion 141 which in turn are operated by the control shaft 10.

The rack 140 has a slot 142 therein at each end of which a roller 143 and 144 is positioned. The control shaft 10 extends through the slot 142 and 20 a cam 150 is mounted on the end of the control shaft which projects through the opposite side of the slot 142.

Roller 143 of the rack member 140 is pressed tightly against the cam 150 by compression spring 25 152 which is mounted on the shaft 153 which is in turn an integral extension of the rack bar 140. The compression spring 152 is compressed between the bracket 155 which is supported by the machine frame and the end 156 of the rack 30 bar 140. The rack is held against the pinion 141 by the idler 160 which bears against the opposite side thereof.

It will now be clear that, as control shaft 10 rotates thus causing a rotation of the cam 150, the cam 150 will bear against the roller 143 and force the rack to move upwardly with respect to Fig. 1, thus rotating the pinion 141.

As the limit of compression of the spring 152 is reached and hence as the limit of movement 40 of the rack 140 is reached, the roller 143 bearing against the cam, and the movement of the cam, permits the rack to be forced in the opposite direction.

As the cam continues its rotation, it bears 45 against the roller 144 which serves as an appropriate bearing in order to cause the rack to follow the movement of the cam 150.

By this means, an oscillatory movement of the rack 140 is obtained, the movement in one direction driving the shaft 132 of the cutting blade 50 in order to effect a cutting of the tape and the movement in the opposite direction having no result upon the shaft 132, but permitting the shaft to remain stationary.

55 Since the rack 140 is integrated with the control shaft 10 and hence with the remainder of the apparatus, any adjustment of the remainder of the apparatus will also result in an adjustment of the period of oscillation of the rack 140 and hence in adjustment in the period of cutting by the cutting mechanism 120.

If desired, and as seen in Figure 6, the rack 140 may oscillate in slots 170, 171 of the frame of the mechanism.

60 The pinion 141 is mounted on the end of the short shaft 180. Shaft 180 carries a plurality of pawl member 181, 181 which are pressed outwardly into engagement with the ratchet member hereinafter described by means of the spring 70 182.

Shaft 180 is appropriately mounted in the frame of the machine, for instance, by means of bearings 185.

Shaft 132 rotates in appropriate bearings 186 75 in the frame of the machine and carries at end

188 thereof a ratchet member 190 which is in the form of a cylindrical sleeve having a securing ring 191 which may be secured, as for instance, by the key member 192 to the end of shaft 132.

The ratchet member 190, as may be seen particularly in Figure 2, is a cylinder which is thus secured to the end of shaft 132 and rotatable therewith.

When the rack 140 is moved in such a manner as to cause the pinion 141 to rotate, shaft 180 is correspondingly rotated. The shaft 180 rotates in a direction indicated by the arrow of Figure 4 and the pawl members 181 will engage with the ratchet portion on the inner periphery of the ratchet cylinder 190 and hence cause a corresponding rotation of shaft 132 to cause a cutting operation of the cutting mechanism 120.

When the rack 140 rotates in the opposite direction thus rotating pinion 141 and shaft 180, likewise in the opposite direction, then the pawls 181 will rotate in a clockwise direction with respect to Fig. 4 and they will not engage the ratchet member on the inner side of the ratchet cylinder 190 and hence no driving power will be communicated to the shaft 132.

As shown in Figure 4, the ratchet member may have 4 teeth 200, 200 so that the engagement of the pawls with the ratchet will occur at only a specific portion of the rotation of the respective shafts and so that when rotation of the member ceases the next rotative operation will again commence at a specific angular position of the shaft 132.

In this manner the regular rotation of the blade 130 of the cutting mechanism is ensured since the angular position at which rotation commences is fixed by the angular position of the teeth 200 of the inner periphery of the ratchet 190.

In the alternative, however, the ratchet may consist of a large number of teeth so that rotation of the shaft 132 may commence immediately upon movement of the shaft 180 and hence of the pawls 181.

In order to prevent back-lash of the shaft 132 or any reverse movement thereof which will throw the foregoing adjustments out of line, I provide a series of pawls 220, 220 (see Figs. 2 and 3) which are urged into position by their respective springs 221, the said pawls being mounted on the collar 230 which in turn is affixed to the frame at 231 in such a manner that the collar 230 cannot rotate.

Hence the shaft 132 which passes through the center of the collar 230 rotates therein and no rotative force whatever is communicated to any of the pawls 220 which are, therefore, stationary.

The ratchet member 190 has in the interior thereof at the points which mesh with the pawls 220, a ratchet having a plurality of teeth which engage with pawls 220.

The pawl and ratchet arrangement at this point is so arranged that rotation of the shaft 132 in the operative direction as previously described, is not resisted, but any reverse rotation is immediately resisted by engagement of the teeth 223 with the pawls 220.

In this manner, the movement in this direction will cause an effective rotation of shaft 132 to cause knife blade 130 to effect the cutting operation while a movement of the rack in the other direction causes no rotation of shaft 132 by reason of the fact that the pawls 181 rotate in a direction opposite to that which is necessary to

cause their engagement with their respective ratchet members.

Likewise, any rotative effect which may be communicated by friction in the reverse direction is resisted by the pawls 220 which are stationarily mounted to engage with the ratchet teeth 223.

Since the rack member is driven by the mechanism hereinbefore described and since it is driven in exact synchronism therewith, the tape-cutting operation is performed at exactly the proper time in order to secure the proper length of tape for the specific box.

The tape is measured off by the rack member 74 in conjunction with the cam 24 and the adjusting member 100 as previously described and the cutting operation takes place at the end of the tape-feeding operation.

Since the tape feeding operation may commence at any point during the cycle, and for shorter tapes the tape-feeding operation is commenced late in the cycle, the fact that the cutting operation takes place always at the end of the cycle permits a predetermination of the exact length of the tape to be cut.

23 By starting the tape feeding operation late in the cycle, a shorter length of tape is cut by the cutting mechanism 120. When the tape-feeding operation is started early in the cycle by an appropriate adjustment of the member 100, then a longer tape is cut. Since the rack member is always integrated with the remainder of the mechanism, it is possible to be certain that the tape-cutting operation will always take place at the end of the tape feeding cycle.

35 In the foregoing I have described a simple tape-feeding and applying mechanism, together with a simplified tape-cutting mechanism.

The tape-cutting mechanism may be mounted, as is noted particularly in Fig. 2, by the brackets 40 250 on the side of the frame of the entire machine and may be integrated with the tape feeding and applying mechanism in order to cooperate appropriately therewith.

Many other adaptations of this preferred embodiment of my device should now be obvious to those skilled in the art.

Accordingly, I prefer to be bound not by the specific disclosures herein, but only by the appended claims.

50 I claim:

1. A cutting means comprising a knife blade mounted on a shaft, a pinion operatively connected to said shaft and a rack in engagement with said pinion, said operative connection between said pinion and shaft transmitting rotative movement to said shaft during rotation of said pinion in one direction and being inoperative to transmit rotative movement in the opposite direction; means for driving said rack to drive said knife shaft.

2. A cutting means comprising a knife blade mounted on a shaft, a pinion operatively connected to said shaft and a rack in engagement with said pinion, said operative connection between said pinion and shaft transmitting rotative movement to said shaft during rotation of said pinion in one direction and being inoperative to transmit rotative movement in the opposite direction; means for driving said rack to drive said knife shaft, said operative connection comprising a shaft carrying said pinion; a pawl and ratchet connection between said pinion shaft and said knife shaft.

3. A cutting means comprising a knife blade mounted on a shaft, a pinion operatively con-

nected to said shaft and a rack in engagement with said pinion, said operative connection between said pinion and shaft transmitting rotative movement to said shaft during rotation of said pinion in one direction and being inoperative to transmit rotative movement in the opposite direction; means for driving said rack to drive said knife shaft, said operative connection comprising a shaft carrying said pinion; a pawl and ratchet connection between said pinion shaft and said knife shaft, the pawl being mounted on said pinion shaft and the ratchet on the knife shaft.

4. A cutting means comprising a knife blade mounted on a shaft; a pinion operatively connected to said shaft and a rack in engagement with said pinion, said operative connection between said pinion and shaft transmitting rotative movement to said shaft during rotation of said pinion in one direction and being inoperative to transmit rotative movement in the opposite direction; means for driving said rack to drive said knife shaft, said operative connection comprising a shaft carrying said pinion; a pawl and ratchet connection between said pinion shaft and said knife shaft, the pawl being mounted on said knife shaft and the ratchet on the pinion shaft.

5. A cutting means comprising a knife blade mounted on a shaft, a pinion operatively connected to said shaft and a rack in engagement with said pinion, said operative connection between said pinion and shaft transmitting rotative movement to said shaft during rotation of said pinion in one direction and being inoperative to transmit rotative movement in the opposite direction; means for driving said rack to drive said knife shaft; and means for preventing rotation of said knife shaft in said opposite direction.

6. A cutting means comprising a knife blade mounted on a shaft, a pinion operatively connected to said shaft and a rack in engagement with said pinion, said operative connection between said pinion and shaft transmitting rotative movement to said shaft during rotation of said pinion in one direction and being inoperative to transmit rotative movement in the opposite direction; means for driving said rack to drive said knife shaft; and means for preventing rotation of said knife shaft in said opposite direction; said means comprising a pawl and

ratchet connection between said knife shaft and a stationary member.

7. A cutting means comprising a knife blade mounted on a shaft, a pinion operatively connected to said shaft and a rack in engagement with said pinion, said operative connection between said pinion and shaft transmitting rotative movement to said shaft during rotation of said pinion in one direction and being inoperative to transmit rotative movement in the opposite direction; means for driving said rack to drive said knife shaft; and means for preventing rotation of said knife shaft in said opposite direction; said means comprising a ratchet on said knife shaft and a pawl mounted on a stationary member.

8. A cutting means comprising a knife blade mounted on a shaft, a pinion operatively connected to said shaft and a rack in engagement with said pinion, said operative connection between said pinion and shaft transmitting rotative movement to said shaft during rotation of said pinion in one direction and being inoperative to transmit rotative movement in the opposite direction; means for driving said rack to drive said knife shaft; and means for preventing rotation of said knife shaft in said opposite direction; said means comprising a pawl on said knife shaft and a ratchet mounted on a stationary member.

9. A cutting means comprising a knife blade mounted on a shaft, a pinion operatively connected to said shaft and a rack in engagement with said pinion; means for driving said rack to drive said knife shaft; said means comprising a cam mounted on a rotatable shaft, a cam follower on said rack, and a spring operatively connected to said rack and urging said cam follower against said rack.

10. A cutting means comprising a knife blade mounted on a shaft, a pinion operatively connected to said shaft and a rack in engagement with said pinion; means for driving said rack to drive said knife shaft, said means comprising a rotatable control shaft, a slot in said rack, said shaft extending through said slot; a cam on said shaft, a cam follower on said rack and means urging said cam follower against said rack.
